GIUSEPPE BIANCHI, OF FIRENZE, ITALY

SAFETY DEVICE FOR ONE-MAN VEHICLES

Application filed June 29, 1931, Serial No. 547,776, and in Italy July 8, 1930.

In order that a train or vehicle driven by a single operator be stopped automatically in the case the motorman or engineer leaves for any reason the seat which is normally occupied by him, various devices are employed which may be classed as follows:

(a) In one of such devices the motorman or engineer is obliged to press continually upon a button or upon a foot-pedal; as soon as he abandons said button or said pedal, an electrical, mechanical or pneumatic device comes into action either immediately or after some time. The chief drawback of this arrangement is that it can be easily modified. The motorman himself, to avoid the necessity of continuously pressing the button or the pedal, may be induced to fix said button or said pedal by any means in a desired position so that the train cannot come to rest. In this case the aim of said device will be quite illusory.

(b) To avoid that employees should artificially alter the working conditions of the apparatus, another class of device has been provided which depends upon the following principle: a device, after a certain time or after a certain distance, puts into action the apparatus which cuts off the motive power and subsequently the apparatus acting upon the brakes, if the motorman does not act, at intervals, upon a button or a pedal. It will be obvious that, as it is very much harder to substitute unduly the intermittent action of the motorman, his class of devices will be less subjected to actions which may alter the operation and frustrate the scope thereof. The main drawback of this class of devices is that the motorman is obliged, at very near intervals, often of a few seconds, to act intermittently upon the button or the pedal, this operation being for the operator a more painful effort than that required by the types of devices mentioned under (a).

The object of this invention is to provide an arrangement in which by means of a mechanical transmission (not shown) the cessation of the motive power of the vehicle and the action of the brakes is obtained, successively, after a certain interval of time or space, if the motorman has left his place, or

if, taken with indisposition he does not execute the usual manipulations required for conducting the train, and, in view of this, without overcharging the motorman with any permanent or intermittent work effort.

The apparatus according to this invention is based substantially upon the following principle: a man being upright or sitting on the driving place of a running vehicle, in order to maintain his upright position, is obliged, necessarily and instinctively, to displace his own centre of gravity either owing to the fact that he must act upon or inspect the various control parts of the vehicle, or, over all, react against the shocks of the car which tend to displace at any moment his body, even slightly, and make him lose his equilibrium.

In the case the motorman is normally standing the device consists substantially of a step formed with a part fixed on the bottom of the vehicle and another portion which, with regard to the former, is susceptible of displacements of feeble amplitude and whereupon the motorman is standing. In the case the motorman is sitting down, the device is also constituted by a step such as the precedent one, on the movable part of which is fixed the seat, or else by a seat composed by a part fastened to the car and another part which, with regard to the former, is susceptible of effecting movements of feeble amplitude and whereon is sitting the motorman. In view of the fact that the principle of this device is identical with the foregoing, either in the case of the step (man in standing position) or in the case of seat (man sitting down), in the following description only the case of the step will be considered.

The feeble relative movements of the movable and the fixed part of the step being acted upon unconsciously by the motorman, will displace necessarily and continually his own centre of gravity, thus giving raise to the intermittent completion of an electrical circuit. If the motorman leaves his seat of his own accord or if, taken with indisposition he falls senseless upon the step, thus considerably displacing his centre of gravity, the intermittent completion and interruption of

the electrical circuit will no more take place, the current being interrupted or permanently cut off.

- The action which produces interruption of the motive power of the vehicle and the operation of the brakes is obtained by means of another apparatus which comes into action after a certain time or distance the vehicle has run over when the current coming from the step remains permanently interrupted or permanently active. If, on the contrary, the movable part of the step, under the action of the movements of the motorman is effecting small displacements which by means of contacts intermittently establish and interrupt the current, the apparatus effecting the interruption of the motive power and the operation of brakes is put into action. In order to fully explain the invention I will now describe a manner of carrying out a step or apparatus for automatically stopping a train. It will be obvious that the invention may be carried out likewise by an apparatus of somewhat different structure with regard to that indicated, but which is still based upon the same principles. Some apparatus embodying the principles of the invention are shown, by way of example only, in the annexed drawing wherein:

Figs. 1 and 2 are diagrams showing respectively a vertical and a plane view of one embodiment of the supporting step.

Figs. 3 and 4 represent in a like manner another embodiment of the invention.

Fig. 5 is a diagrammatical view of a mechanism adapted for cooperating with the said step and for controlling the provided safety devices, not shown on the drawing, as they are not claimed by the present application.

Referring to Fig. 1 of the drawing a diagrammatical form of the step is represented which embodies the object of breaking or closing an electrical circuit when the motorman being upright on the step is effecting, consciously or involuntarily, feeble movements.

The step is composed of a plate D suspended at its centre by an axis P and supported close to its periphery by a row of springs m , m' adapted for balancing its weight and impeding the metallic rim of said disc or plate D to come into contact with a series of contact members C, C' spaced along the periphery of the movable part of the step.

The electric contact members C, C' may be of opposite polarity as shown in Figures 3 and 4, the contacts C having all like polarity and contacts C' being insulated so that they cannot close the circuit between the lines L, L' and having only as their object to hold the movable step at the same level as contacts C when the step is inclined under the action of a weight. In this case one of the terminals of the circuit comes into contact with the contact members C and the other one with the movable part of the step.

Until the motorman has mounted on the step, the electrical circuit which terminates at the contact members C, C' in Fig. 1 or at the contact members C of the step represented in Fig. 3 will remain open. When the motorman or a dead weight enters the step, the latter will be displaced or tilted in such a manner as to be supported at P and at a point P' of the circumference which results from the connection of P with the projection of the centre of gravity G of the load. Then two cases may arise: either the point P falls between two peripherally disposed contact members C, C' of Figure 2, and in this case it will be obvious that the electrical circuit will remain closed through the contact members C and C' adjacent to the point P'; or the point P' coincides with a contact C or with a contact C' and the circuit will remain open. In the case of Figs. 3 and 4 point P' coincides with a contact C and the circuit will remain closed across the movable step and the contact C. If, however, said point coincides with an insulated contact C' the circuit will remain open.

When the vertical line passing through the centre of gravity of the body placed on the step is not displaced with regard to G it will be apparent that the electrical circuit remains always either closed or open. This will happen when the motorman does not any longer give any signs of life or if an inert body rests on the step.

It could be objected that the shocks of the running vehicle displace the projection of the centre of gravity of the inert body in such a manner as to subsequently displace the point P' of contact on the circumference and render intermittent the electric contact and thus the current, as it would result with a living motorman on the step. To this objection it may be replied that the displacement of the projection G of the centre of gravity under the action of the shocks of the running vehicle upon those of an inert body lying on the step cannot exceed a certain amplitude. The distance between the contact members C and C' may be chosen sufficiently great so that the latter be greater than said amplitude.

The displacement of the centre of gravity and of its projection on the step, D, and, consequently of the contacting point P' is, on the other hand, very important when on the step is the motorman who continually displaces his own centre of gravity in relation with the movements he is obliged to effect for control the apparatus and his sufficiently instinctive movements which are necessary to ensure his equilibrium.

It will be obvious that the movable step in the case of a motorman standing upright or the movable seat in the case of a motorman sitting down may present very different shapes from those previously described. In

all cases either the seat or the step should satisfy the following requirements:

(1.) When no load is applied on the step or seat, the electric contacts should maintain 5 a permanently open or permanently closed circuit.

(2.) Said electric contacts should be spaced and of such size that the action of the shocks of the vehicle upon an inert body resting 10 upon the step or seat could not render intermittent the contacts.

(3.) When, on the contrary, a living body rests on the step and which continually and 15 energically reacts against the shocks of the vehicle tending to make him lose his equilibrium, the contacts should be constituted in such a manner as to render intermittent the passage of the current.

Fig. 5 is a diagrammatic view of one possible form of the apparatus which causes first 20 the interruption of the motive power of the car and subsequently the operation of the brakes when the current coming from the step remains branched off or permanently 25 interrupted.

An electromagnet E is fed by the current established or interrupted by the contacts of the movable member of the step D. Said electromagnet attracts an armature H having 30 two bosses d and d' which in the attracted or released position of the armature urge the rod A towards the screw V while in any other intermediate position of the armature the rod A is spaced from the screw V by the action 35 of the spring M. On the rod A a weight Q may freely slide in the same direction as the rod, said weight being provided, at the side of the screw V, with a helically threaded portion having the same pitch as the screw. The 40 screw V is maintained in the same rotating direction by any suitable driving mechanism having a constant speed independent from that of the vehicle or, through a mechanical drive, by the vehicle itself in such a manner 45 that the speed of rotation of the screw be proportional to the speed of the vehicle.

It will be easily understood that when the electromagnet is permanently energized or inenergized, the weight Q being urged against 50 the rotating screw is engaged with the latter and if lifted at a speed of displacement which is proportional to the pitch of the screw and its rotary speed. If nothing occurs to vary the current conditions in E, the 55 weight Q will move until it reaches the position Q', i. e. the top of the screw. Prior to reaching this point the weight Q will successively contact with the points K, K, etc. which, through a mechanical transmission, 60 not shown, will actuate the apparatus interrupting the motive power and the braking mechanism of the vehicle.

If, on the other hand, during the ascension of Q towards the end of the screw, current is 65 fed to or withdrawn from the electromagnet

F, and, consequently, if the armature H moves in one or in another direction, the spring M will be enabled to remove for an instant the rod A and the weight Q from the screw V. In this manner the weight Q falls 70 down, thus being prepared to immediately repeat its ascensional movement. It will be obvious that the weight Q will be unable to effect the ascension until the contact with k, k' etc. is established and will therefore cause 75 the stopping of the vehicle only if in the meantime the electromagnet has not been active. Consequently, if upon the step is a living body which is moving continually thus producing the intermittence of current with- 80 in the electromagnet E, it will be possible, by suitably choosing the rotary speed of the screw V of its length and pitch, that the weight Q never accomplishes its complete course. On the contrary, this complete 85 course will be accomplished when for a certain interval of time the step remains motionless this condition corresponding to the fact that nobody is on the step but only an inert weight so that the current remains perma- 90 nently interrupted or permanently active.

What I claim is:

1. An electrical safety device for trains arranged to apply the brakes having in combination a base member, a tiltable plate positioned above said member, means extending from the base member for pivotally supporting the plate medially thereof, circumferentially disposed electrical contacts positioned between said member and said plate for closing an electric circuit when the plate is moved into engagement therewith, yieldable means normally maintaining the plate away from said contacts, and means upon the plate being depressed for closing the electrical circuit and applying the brakes. 95

2. An electrical safety device for trains arranged to apply the brakes having in combination a base member, a tiltable plate positioned above said member, means extending from the base member for pivotally supporting the plate medially thereof, circumferentially disposed contact members positioned between said base member and said plate for closing an electrical circuit when the plate is tilted upon being depressed by a body, certain of said contact members being of the same polarity and others being insulated so as not to close the circuit when the plate is moved into engagement therewith, and means normally maintaining the plate out of engagement with said contact members. 110

3. An electrical safety device for trains arranged to apply the brakes having in combination a base member, a tiltable plate positioned above said member, means extending from the base member for pivotally supporting the plate medially thereof, circumferentially disposed contacts positioned between 115

said member and said plate for closing an electric circuit when the plate is moved into engagement therewith, yieldable means normally maintaining the plate away from said contacts, means controlling the electrical circuits in accordance with the position of said tilttable plate when depressed by movement of the engineer's foot thereon, and means upon an inert body depressing said plate for closing the circuit and causing the brakes to be applied.

4. An electrical safety device for trains arranged to apply the brakes having in combination a base member, a tilttable plate positioned above said member, means extending from the base member for pivotally supporting the plate medially thereof, circumferentially disposed contact members positioned between said base member and said plate for closing an electrical circuit when the plate is tilted upon being depressed by a body, said plate having means coacting with said contact member for intermittently passing the current through the circuit when the plate is depressed during the normal operation of the device, but preventing the intermittent passage of the current when the plate is depressed by an inert body, and means normally maintaining the plate out of engagement with said contact members.

5. An electrical safety device for trains arranged to apply the brakes having in combination a base member, a tilttable plate positioned above said member, means extend-

ing from the base member for pivotally supporting the plate medially thereof, circumferentially disposed contact members positioned between said base member and said plate for closing an electrical circuit when the plate is tilted upon being depressed by a body, means for opening and closing the electrical circuit in accordance with the depressed position of the plate by the foot of the engineer or motorman resting thereon, means upon the plate being depressed by an inert body for applying the brakes, and means normally maintaining the plate out of engagement with said contact members.

6. An electrical safety device for trains arranged to apply the brakes having in combination a base member, a tilttable plate positioned above said member, means extending from the base member for pivotally supporting the plate, circumferentially disposed electrical contact members positioned between said base member and said plate for closing an electric circuit when the plate is tilted upon being depressed by a body, operating instrumentalities operatively connected to the safety device and the brakes whereby upon the plate being depressed by an inert body for automatically operating the brakes, and yieldable means normally maintaining the plate out of engagement with said contact members.

In testimony whereof I have hereunto set my hand.
